UNITED STATES PATENT OFFICE.

JAMES H. HAYDEN, OF COLORADO SPRINGS, COLORADO, ASSIGNOR OF ONE-
THIRD TO HENRY BLISS HAYDEN, OF SAME PLACE.

DEVICE FOR CLOSING AND OPENING COVERS FOR INK-WELLS.

SPECIFICATION forming part of Letters Patent No. 439,148, dated October 28, 1890.

Application filed August 19, 1890. Serial No. 362,400. (No model.)

To all whom it may concern:

Be it known that I, JAMES H. HAYDEN, a citizen of the United States, residing at Colorado Springs, in the county of El Paso and 5 State of Colorado, have invented certain new and useful Improvements in Devices for Closing and Opening Covers for Ink-Wells; and I do hereby declare the following to be a full, clear, and exact description of the invention, such as will enable others skilled in the 10 art to which it appertains to make and use the same.

This invention relates to certain novel improvements in devices for closing and opening covers for ink-wells and the like; and it 15 consists in the construction and novel arrangement of parts, as will be hereinafter fully described, whereby a lid or cover is automatically caused to close the mouth of a 20 well to be continuously covered when not in use.

The annexed drawings, to which reference is made, fully illustrate my invention, in which—

Figure 1 represents a front view of an ordinary ink-well, showing my device applied thereto. Fig. 2 is a perspective of the clamping-bars detached from the ink-well. Fig. 3 is a side view of the adjustable clamp.

Referring by letter to the accompanying drawings, A represents an ordinary ink-well to which my device is attached, and B designates a clamp therefor, which latter consists of two spring arms or bars *a a'*, the former of which is constructed with a horizontal portion or arm *b*, having a series of indentations *b'* in its outer face and an outwardly-turned lip *c*, having a slot *c'* through it. The transverse horizontal portion or spring-arm *d* is bent at right angles to the portion *b*, and the 30 extended end *d'* thereof is bent at right angles to the portion *d*. The said bars *b*, *d*, and *d'* are formed integral. The spring-arm *a'* consists of the transverse bar *e* and the horizontal bar *e'*, which latter is bent at right angles to said bar *e* and is provided at its end *f* with an inwardly-projecting pin *f'*, which 35 is designed to engage one of the series of indentations in the arm aforesaid when the clamp is applied to an ink-well. These spring- 40 arms are provided with pads *g g* on their in-

ner faces and are designed to assist the spring-arms in firmly holding the clamp to the ink-well, as well as preventing the arms from contact directly with the ink-well and thus saving the latter from injury.

55
C indicates a standard, at the lower end of which is formed a slotted guideway *h*, the offset portion *h'* of which is female screw-threaded to receive a screw *i*, by which the standard is removably secured to the extended arm of 60 the angular spring-bar aforesaid. This standard is constructed with an offset or short arm *i'*, in the upper face of which is made an indentation or pivotal bearing *j*, and an upper offset or short arm *j'* is provided, having 65 therein a vertical female screw-threaded opening, in which is placed a thumb-screw *k*, in the lower end of which is an indentation or pivotal bearing *l*, which bearings are designed to receive the points of a pivotal bar, which 70 I will now refer to.

D designates a pivotal bar consisting of a short arm *i'*, at the end *m* of which are provided male screw-threads *m'*, which receive a female-threaded nut *n*, and the long arm *n'*, 75 at the outer end of which is a hook *o* and a loop *o'*, which is secured thereto and extending at right angles to said bar. This bar tapers outwardly in either direction from the point *p*, at which point extend two short arms 80 *p' p'* at right angles to said bar, which short arms taper to a point and form a journal or pivot for said bar when the latter is connected to the standard. The upper portion of this standard inclines forwardly, as shown at *r*, 85 thus causing the indentations in the offset and end of the thumb-screw to be out of a perpendicular line with one another, thereby providing means whereby the pointed pivotal connection of the swinging bar inclines upwardly and forwardly.

E represents a cover or lid for the ink-well, in the center of which is an eye *r'*, which engages the hooked end of the pivoted bar aforesaid and forms a swivel-connection at this 95 point. In connecting the parts to one another the two spring angular bars are connected by passing the horizontal portion having the pin in its end through the slot in the upturned end of the bar having the series of indenta- 100

tions, after which the spring-arms are passed on each side of an ink-well and the pads forced against the same. At the same time the pin enters one of the indentations, thus firmly gripping said ink-well by the spring-arms having the pads.

The standard is attached to the extended arm by the latter passing through the slot in the lower end, after which the standard is 10 adjusted—*i. e.*, moved forward—toward the ink-well until the cover comes directly over the mouth of the same, after which the screw *i* is tightened, thus holding said standard in a fixed position. The points of the pivotal bar 15 are then inserted in the bearings, and the screw is turned sufficiently to retain said points in place, thereby providing pivotal connection or bearing between the standard and arm aforesaid, after which the nut is adjusted 20 to a nicety in order to balance the beam or pivoted bar.

The angular bars which grasp the ink-well can be adjusted to fit snugly any size or shape 25 ink-well or the like simply by adjusting the same, and the pin catching in the indentations in one of the bars holds them firmly to one another.

In uncovering the ink-well the operator simply touches the wire loop with his pen, 30 which causes the lid to move rearwardly and upwardly, the bar turning on its pivot, and remains off the ink-well sufficient time to permit the pen being dipped therein when the lid returns automatically and closes the opening in the ink-well. The movement this lid receives in leaving the ink-well is inclined, and as the lid goes back it rises, caused by the 35 pivotal points of the bar *D* being out of a vertical line with one another, and provides 40 gravitation, whereby the lid is brought back slowly over said well. The peculiar motion given to this swinging arm permits a gentle easy movement to the ink-well cover. The weight or nut on the opposite end to that of 45 the hooked end of this beam or bar serves to balance said beam nicely, and the balance can be obtained by simply giving said nut a slight turn, causing it to move toward or from the pivotal connection or standard. It will thus 50 be observed that by my device the operator simply touches the wire loop, forcing the bar with its lid backward, and after dipping the pen the ink-well is closed by the lid returning

by gravitation. The operator never handles the lid either in opening or closing the ink-well, and it is ornamental, easily and quickly applied to an ink-well or the like, is durable, and at the same time cheap to manufacture. In the drawings I have shown in dotted lines 55 a receptacle for a sponge or bristles holder, which can be used, if preferred, in connection with my device.

Having thus described my invention, what I claim as new, and desire to secure by Letters Patent, is—

1. In combination with an adjustable clamp for ink-wells, a standard having upper, lower, and central offsets and bearings for the standard, and pivoted bar *D*, the former being removably secured to the adjustable spring-clamp *B* by means of the screw *i*, substantially as described, and for the purpose specified.

2. In combination with the adjustable spring-clamp *B*, the standard *C*, provided with the offset *h'*, having therein an opening 75 through which a clamping-screw *i* is passed, and offsets *i'* and *J'*, through the latter of which is passed a set-screw for securing the pivotal bar *D* to the standard, substantially as described.

3. The combination, with the adjustable spring-clamp, the standard having the guide-way *h*, and the respective offsets and bearings, of the pivoted bar *D*, provided with short arms *p p'* and screw-threads at its rear end to receive an adjustable screw-threaded nut or weight and having secured to its forward end a loop *o'*, and cover *E*, substantially as described, and for the purposes specified.

4. The within-described device for automatically closing an ink-well or other receptacle, consisting of an adjustable clamp composed of two angular bars adapted to be secured to an ink-well or other receptacle, a standard horizontally adjustable upon one of these angular bars, and a beam or bar pivoted to this standard and provided with a cover, all substantially as and for the purposes set forth.

In testimony whereof I affix my signature in presence of two witnesses.

JAMES H. HAYDEN.
